UNITED STATES PATENT OFFICE.

WILLIAM B. HASKINS, OF LOS ANGELES, CALIFORNIA,

LOW-WATER SAFETY APPARATUS FOR STEAM-BOILERS.

1,162,160.

Specification of Letters Patent. Patented Nov. 30, 1915.

Application filed August 17, 1914. Serial No. 857,274.

To all whom it may concern:

Be it known that I, WILLIAM B. HASKINS, a citizen of the United States, residing at Los Angeles, in the county of Los Angeles 5 and State of California, have invented new and useful Improvements in Low-Water Safety Apparatus for Steam-Boilers, of which the following is a specification.

My invention relates to improvements in 10 low water safety apparatus for steam boilers, having corrugated hollow disks apt to expand in proportion to the temperature rise due to an increase in the heat; and the objects of my improvements are, first, to provide 15 outlet openings for alarm and for the connection of fuel feeding shut off valves; and, second, to provide a fuel feeding shut off valve having hollow disks apt to shut off the fuel after the alarm has been blowing; 20 the invention consisting in the combination, construction, and arrangement of devices hereafter described and claimed.

In the accompanying drawings: Figure 1 is a vertical sectional view of my low-water 25 safety apparatus and of my fuel-feeding shut-off-valve, connected by a pipe. Fig. 2 is one element of the hollow disks in vertical sectional view. Fig. 3 is one element in top view. Fig. 4 is one element in expanded 30 position. Fig. 5 is my device attached to a boiler.

In accordance with my invention, the safety apparatus is shown on the drawing in Fig. 1 as being mounted in a main-casing 1, 35 into which on the upper end is screwed a valve-casing 2, especially constructed for this combination, being closed by a cap 3 on the top end and having outlet openings to the sides as indicated by 4. The valve-casing 2 being in communication with the main-casing 1 by an overflow 5. The bottom end 6 of the main-casing communicating with the steam boiler at the low water level as indicated by 7. A cylinder 8 extending down- 40 wardly from the valve-casing 2, being surrounded by a steam passage 9, is arranged to take up hollow disks 10. A valve 11, arranged above the hollow disks, being provided with a downwardly projecting stem 45 12. The valve is to engage with the valve seat 13. Fig. 2 at 14 shows corrugations, which allow the disks to expand to a great height and also it will show that these disks can be made in a great variation as long as

there is room enough inside to give good results for the necessary expansion. The opposite plates are connected as indicated by 15: one end is always wider than the other to fit into each other. At 16 is shown how the whole disks can be attached together, 60 making the full set of disks water- and airtight. The arrangement at Fig. 5 is made to connect my device to a fuel feeding valve. The incoming steam at 17 may be taken from one of the outlet openings 4 see Fig. 1, the reason herefor will be given later. The heating- and expanding-parts will be the same as explained on Fig. 1, only an extra outlet opening 18 is provided for the waste steam. This apparatus may be attached at 70 a suitable place near the burner at the end 19. Incoming fuel from 20 passing the valve 21, which is open unless steam from the low water safety apparatus closes it, will pass the end 19 to the burner. 75

In case that the water in the boiler is coming below the low water level, as indicated at 7, steam is going into the opening 6 and further into the surrounding passage 9, heating the cylinder 8 and at the same time the 80 hollow disks 10, which, as being closed, will expand by the inclosed air, pushing up the valve 11 by stem 12, thus giving free passage for the steam through outlet openings 4. Openings of this kind may be had and put in 85 as many as available; for alarm-valve, whistle, fuel feeding shut-off-valves, etc. To one of these outlet openings 4 is a tube 22 connected, bringing steam from the low water safety apparatus, to the inlet 17 of the fuel feeding 90 shut off valve, after the disks in the low water safety apparatus have been expanded and the valve lifted, giving free passage to the steam to escape through the outlet openings 4, blowing out of one of these outlet 95 openings for alarm and at the same time giving steam to the fuel feeding shut off valve, as described above. Using it for my fuel feeding shut-off-valve, it has the advantage, that after the alarm valve has been blowing 100 it gives time enough to fill up the boiler with water before the shut-off-valve is warm enough to turn off the fuel.

The disks are shown as being hollow and closed for the reason that air, water, or any 105 kind of liquid, being inclosed, will expand very much by the increasing heat and push out the flat side walls of the disks. To give

better results, with more expansive metal, corrugated disks are provided as more complete improvement.

Having thus described my invention, I claim:—

In a low water safety apparatus for steam boilers, the combination with a fuel controlling device having a valve therein and sensitive expansion disks for operating said valve to control the supply of fuel, of a water level actuated device having a connection adapted to communicate with a steam boiler at the low water level, a valve therein adapted to permit the egress of steam partly blowing out into the open air for alarm and ex-

pansion disks for operating said last named valve, and of a pipe connection leading from the steam egress of the water level actuated device to the fuel controlling device and adapted to pass steam, simultaneously with the alarm-blowing, adjacent to the first mentioned expansion disks, whereby the fuel supply is controlled by the fluctuations of the water level, all substantially as described.

In testimony whereof I hereunto affix my signature in the presence of two witnesses.

WILLIAM B. HASKINS.
